UNITED STATES PATENT OFFICE

139,333

DESIGN FOR A FLUTE

Josephus Thompson, Covington, Ohio, assignor
of one-third to Grossman Music Company,
Cleveland, Ohio, a partnership

Application July 14, 1944, Serial No. 114,402

Term of patent 14 years

(Cl. D56—1)

To all whom it may concern:

Be it known that I, Josephus Thompson, a citizen of the United States, residing in the city of Covington, county of Miami, and State of Ohio, have invented a new, original, and ornamental Design for a Flute, of which the following is a specification, reference being had to the accompanying drawing, forming a part thereof.

I claim:

The ornamental design for a flute, substantially as shown.

JOSEPHUS THOMPSON.
